FRAME FOR HANDBAGS, PURSES, OR
THE LIKE

George S. Merk, Flushing, N. Y.

Application May 24, 1934, Serial No. 727,327

3 Claims. (Cl. 150—29)

This invention relates to handbags and purses or like structures, and more particularly to the frames for handbags, purses or like structures.

An object of this invention is the provision of a frame for handbags which embodies the minimum number of parts so as to reduce the manufacturing cost of the completed handbag, while at the same time producing a frame which will withstand hard usage.

10 Another object of this invention is to provide a frame wherein the usual type of filler is eliminated, the edges of the bag structure being firmly clamped between clamping flanges or jaws fixed to the frame.

15 A further object of the invention is the provision of a novel means for clamping the bag structure thereto which includes flanges between which the material of the handbag is firmly held, the clamping devices not only reducing the number of parts in the frame, but also providing a simple means for securing the handbag to the frame.

20 A still further object of this invention is the provision of a frame wherein the confronting faces of the two frame portions will be smooth and the clamping means will not become loosened during the use of the handbag.

25 Other objects will be apparent from the following detailed description of this invention, and 30 from the drawing, wherein:

Figure 1 is a perspective view of a handbag frame constructed according to an embodiment of this invention having a fragmentary portion of a handbag structure secured thereto;

35 Figure 2 is a fragmentary perspective view of the frame shown in Figure 1;

Figure 3 is an enlarged sectional view taken on the line 3—3 of Fig. 1;

Figure 4 is a transverse sectional view of a 40 modified form of this invention;

Figure 5 is a view similar to Figure 4 of another embodiment of this invention.

Figure 6 is a view similar to Figure 4 of a further embodiment of this invention, and

45 Figure 7 is a front view of a modified form of the embodiment shown in Figure 2.

50 Referring to the drawing wherein like characters of reference designate like parts, the numerals 10 and 11 designate complementary frame sections which are hinged or otherwise secured together for movement relative to each other, as at 13. The two frame sections 10 and 11 are identical in construction, and the description of one of these sections will apply equally as well to 55 the other section.

These frame sections 10 and 11 are adapted to have secured thereto the free edges of a handbag B, which is shown in fragmentary form in Figures 1 and 3. The frame sections 10 and 11, each comprise as shown in Figures 1, 2 and 3 a single piece of metal having a flat inner wall 12. 5 This wall 12 at its upper or outer edge is bent outwardly as at 14 so as to form a flange or outer clamping member, which in the present instance is corrugated so that the material of which the bag B is constructed will be firmly held in place.

The lower, or inner edge of the wall 12 is reverted or bent upon itself as at 15, and this reverted portion 15 is preferably disposed in face abutting relation to the outer face of the wall 12, 15 and may be secured firmly against the outer face of the wall 12 in any desired manner, such as spot welding, soldering, riveting or the like. The outer wall portion 15 has its upper or outer edge bent angularly as at 16 to form a second flange 20 or clamping member which is spaced from the first clamping member or flange 14. As shown in Figures 1, 2 and 3, this second or inner flange 16 is flat, and this flange 16 coacts with the flange 14 in firmly holding the edges of the bag B to the 25 frame.

In Figure 4 there is shown a modified form of this invention wherein the inner wall or body member 12a is flat as in Figures 1, 2 and 3. In this form, however, the outer flange or clamping member 14a has a smooth or flat surface, and this clamping member 14a is made integral with the inner flange or clamping member 16a by forming a channelled member substantially U-shaped in transverse section with the bight 17 35 thereof secured in any desired manner as by soldering, welding or similar means, to the outer surface of the wall member 12a. In order to firmly clamp the bag between the clamping flanges 14a and 16a, I have provided a rib or piercing 40 member 18 on the outer edge of the inner clamping member 16a which is bent in the direction of the outer flange 14a. Initially the two clamping members 14a and 16a are disposed in divergent relation so that the material of the bag may be 45 readily placed therebetween. When the edges of the bag are placed between the clamping flanges 14a and 16a the two members may be pressed together until they assume the position shown 50 in Fig. 4, and in this position the rib 18 will compress the material of the bag more tightly than the clamping members 14a and 16a and at a point outwardly of the edge of the bag. It 55 will, of course be understood that if desired only

the inner clamping member 16a may be bent on an oblique angle to the bight 17.

Another embodiment of this invention is shown in Figure 5, and in this embodiment the wall member 12b has the outer clamping flange or member 14b integral therewith and bent at a right angle thereto. The outer wall 15b in this form of the invention is not integral with the wall 12b, but is secured in face abutting relation to the wall 12b in any desired manner, as by soldering, welding, or any other well known securing means. The upper or outer edge of the wall 15b is bent angularly as at 16b to form a second clamping flange or member substantially parallel with the flange 14b. The outer or free edge of the flange 16b has a rib or material piercing member 18b which extends in the direction of the outer flange 14b.

A further embodiment of this invention is shown in Figure 6, wherein the inner or body wall 12c has the outer flange or clamping member 14c integral therewith. In this form, however, the inner or second clamping flange 16c is secured in edge abutting relation to the outer surface of the body wall 12c. The means by which the member 16c may be attached to the wall 12c may be by welding, soldering or any other conventional securing means. The inner member 16c has a rib or material piercing member 18c on the free edge thereof which is adapted to hold the material of the bag in the same manner as the rib or elongated tang 18 shown in Figure 4.

In the assembly of a handbag having a frame as hereinbefore described, the free edges of the bag, normally constituting the mouth of the bag are inserted between the clamping flanges or members 14 and 16, and initially at least one of these flanges may be bent with the outer edge thereof spaced from the adjacent edge of the other member or flange a distance greater than the inner edge. The edges of the bag material are then inserted between the two clamping members or flanges, and then at least one of these clamping members or flanges is bent toward the other so as to firmly grip the bag material and firmly hold the material to the frame.

In Figure 7 is shown a partial front view, broken off, showing the lower edge 16 provided with a plurality of pressed out tits 20 having sharp points which upon pressure being applied to the member 16, against the member 14, firmly hold the leather or other covering.

It will be apparent from the foregoing that by providing a frame structure as hereinbefore described the problem of assembling the parts of the bag is simplified, and at the same time the constructional costs of the bag are reduced considerably. 5

While I have shown several forms of a frame for a handbag or purse, it will be apparent that further changes may be possible, such changes being limited only by the scope of the following 10 claims:—

What I claim is:

1. As a new article of manufacture, a handbag frame comprising a pair of hinged members, each having a flat portion parallel to each other and contacting face to face when the frame is closed, and each having a pair of bag material clamping members at the upper outer portion of the flat portions, extending outwardly substantially at right angles to the flat portions, the outer surfaces of the pair of upper clamping members forming when the bag is closed a substantially continuous surface. 20

2. As a new article of manufacture, a handbag frame comprising a pair of hinged members, each having a flat portion parallel to each other and contacting face to face when the frame is closed, and each having a pair of bag material clamping members at the upper outer portion of the flat portions, extending outwardly substantially at right angles to the flat portions, the outer surfaces of the pair of upper clamping members forming when the bag is closed a substantially continuous surface, each hinged member being formed by a piece of metal bent upon itself near the central part of the piece, and having each of the free ends forming the clamping members in spaced relation to each other. 30

3. As a new article of manufacture, a handbag frame comprising a pair of hinged members, each having a flat portion parallel to each other and contacting face to face when the frame is closed, and each having a pair of bag material clamping members at the upper outer portion of the flat portions, extending outwardly substantially at right angles to the flat portions, the outer surfaces of the pair of upper clamping members forming when the bag is closed a substantially continuous surface, and certain of the clamping members being provided with corrugations. 40
